UNITED STATES PATENT OFFICE.

RUDOLF WAGNER, OF HAMBURG, GERMANY, ASSIGNOR TO STAR CONTRAPROPELLER LTD. A/S., OF CHRISTIANIA, NORWAY.

DOUBLE PROPELLER FOR WATER AND AIR CRAFT.

Application filed December 30, 1919. Serial No. 348,388.

To all whom it may concern:

Be it known that I, Doctor RUDOLF WAGNER, chief engineer, a citizen of the German Republic, residing at Hamburg, Germany, 5 Bismarckstr. 105, have invented certain new and useful Improvements in Double Propellers for Water and Air Craft, of which the following is a specification.

This invention comprises improvements in 10 and connected with screw propellers particularly applicable for the propulsion of water craft and aerial craft.

In known types of marine propellers in combination with fixed counter propellers arranged behind the principal propeller in the normal direction of travel, the diameter of the counter propeller is approximately as large as the diameter of the main propeller. The intention being to utilize, as far 20 as possible and by means of the fixed guide blades, the tangential motion of the water close to the periphery of the propeller. In order to further achieve this purpose, it has also been suggested to make the counter propeller of even larger diameter than the main propeller.

In practice, these types of double propellers have been found to possess considerable drawbacks. For example, the outer parts of 30 the counter propeller are easily damaged when the ship happens to ground or to strike against a bank or object. Experience has shown, also, that by the strong rhythmical variation of the direction of flow to which the outermost threads of water are subjected, according to the varying distance between the blades of the main propeller and the blades of the counter propeller, seen in the direction of rotation, the outer parts of the 40 counter propeller blades are subjected to considerable bending stresses. These stresses increase as the diameter of the counter propeller approaches, or even exceeds, that of the main propeller. Therefore, the blades of the counter propeller have, in such cases, to be made stronger at their inner sections, thereby involving the disadvantage of an increased axial resistance to the flow. The gain at the outer periphery is therefore again partly compensated by the loss at the inner parts; besides the strengthening of such inner parts obviously entails a greater weight.

In consideration of these circumstances

and according to the present invention, a 55 diameter is deliberately adopted for the counter propeller, arranged behind the principal propeller, which is smaller than the diameter of the main propeller: in order to render such construction feasible without 60 impairing the maximum efficiency of the propeller, the present invention further provides that the main propeller has a variable pitch increasing radially towards the hub. Thereby the tangential action of the water 65 is reduced at the periphery but is more powerful in the centre. Therefore, the outermost parts of the counter propeller, under such conditions, may be dispensed with, as the comparatively small gain due to their 70 retention would be discounted by the displacement and frictional resistance due to such parts.

The radial variation of pitch is, in this case, not only to be understood in the ordinary way, that is to say having relation to the variation of the pressure surface of the screw, but it embraces the variation of the so-called effective pitch. According to modern views, for instance, a propeller with a 80 constant pitch of the pressure surface may be considered as having a certain radial pitch increasing from outside to inside owing to the thickness of the blades increasing towards the hub or boss. 85

The increased tangential motion of the water in the central sections will naturally entail an increased necessity of providing a counter propeller, and in addition, the efficiency of such counter propeller under these 90 conditions is especially favourable.

Numerous experiments with ordinary single propellers have shown that a radial variability of pitch does not afford any increase of the efficiency worth mentioning. Only 95 when such a propeller is in co-operation with a counter propeller, does the employment of a pitch radially increasing towards the centre become reasonable and its advantage become apparent.

In this case, the action of the main propeller is concentrated to the centre and therefore the diameter of the counter propeller may be smaller than that of the main propeller.

The two stipulations, viz., smaller diameter of the counter propeller and radial increase of the pitch of the main propeller,

are thus complementary and afford the advantage of a smaller, safer, lighter and cheaper counter propeller.

In general, it may be said, within certain limits, that the counter propeller may be made reduced in diameter accordingly as the pitch of the main propeller is varied or is increased towards the centre. Obviously there are certain limits for such increase of pitch. Most recent experiments have shown that the diameter of the counter-propeller should not be larger than approximately 0.90 to, as the maximum, 0.95 times the diameter of the main propeller. For instance in case of too great an increase of pitch the outer surface of the main propeller may no longer produce a thrust, and, on the other hand, strong eddies may be formed behind its inner blade sections.

20 The relation between the diameter of the counter propeller and the variations of the pitch of the main propeller may be an inverse linear relation and it may also be determined by any rule of inverse ratio.

25 The invention is not concerned with a known arrangement of double propeller with fixed directing blades or distributors mounted in front of the principal propeller in the direction of travel and having a 30 smaller diameter than the principal propeller. This arrangement involved a fundamentally different principle inasmuch as the directing or distributing blades of this counter propeller communicated to the water a tangential speed opposite direction to that of revolution of the principal propeller prior to such water coming into contact with the principal propeller.

In order to enable the present invention 40 to be readily understood, reference is made to the accompanying drawing which Fig. 1 illustrates in side elevation one constructional example of a propulsion device comprising a main propeller and a counter propeller in accordance with these improvements mounted at the stern of a boat;

Figs. 2, 3, 4 and 5 are transverse sections taken on lines 1—1, 2—2, 3—3, and 4—4 of Fig. 1 respectively;

50 Fig. 6 is a rear elevation of the device shown in Fig. 1.

In the drawing, *a* is the main propeller with its pitch increasing radially towards the boss, or hub at the center, the emerging 55 or trailing edge *b* being straight in side elevation for simplifying the construction of

the fixed counter propeller *c*. The diameter *D*² of the latter is, according to the present invention, smaller than the diameter *D*¹ of the main propeller *a*, for sake of greater 60 safety of service, this diameter has been made even smaller than indicated by the aforesaid limit of 0.9—0.95.

In the embodiment shown, the counter-propeller *c* consists of 6 blade-like arms, 65 which may be either made in one piece with a common hub *d* or separately attached to such a hub.

The vertical blades registering with the rudder stem may also be made in form of a 70 main arm, hollow, if necessary, which may serve for attaching the counter-propeller to the hull of the ship, and which for this purpose may be connected with the rudder stem *a*, for instance, by means of bolts *f*, *g*, *h* 75 or any other means. After the screws *f*, *g*, *h* and the divided fixed protection hood *i* have been removed, the counter-propeller *c* may be drawn away sideways from the stem, and the main propeller *a* may be taken off. 80

With twin-screw ships the counter-propeller may be attached by two of its blades being elongated up to the hull of the ship.

What I claim and desire to secure by Letters Patent of the United States, is:

1. A double-propeller for water and aircraft, comprising, a rotary main propeller fitted with blades which have a pitch increasing radially towards their axis of movement, and a counter-propeller the 90 diameter of which is inversely dependent upon the variation of the pitch of the main propeller, the diameter of the counter-propeller being the smaller, the more the radial pitch of the main propeller is increasing. 95

2. A double propeller comprising a rotating main propeller fitted with blades which have a pitch increasing radially towards the centre, and a fixed counter propeller arranged behind the main propeller 100 and composed of fixed curvilinear blades, and having a diameter smaller than the diameter of the main propeller and inversely dependent upon the variation of the pitch of the main propeller, the said diameter 105 being reduced in accordance with the increase in the radial pitch of the main propeller.

DR. RUDOLF WAGNER.
